INFLATABLE FLOTATION DEVICE

Daniel Mapes, Upper Montclair, N. J., assignor to
 Walter Kidde & Company, Inc., New York,
 N. Y., a corporation of New York

Application April 8, 1933, Serial No. 665,090

10 Claims. (Cl. 9—2)

The present invention relates to inflatable flotation devices of the general type now extensively employed as marine life-saving devices, and is equally adapted to for use with life-vests or belts 5 for individual use, life-boats or rafts for the use of one or more persons, and so called "flotation bags" such as are now extensively used for preventing the sinking of aeroplanes not otherwise equipped to float when forced to descend upon a 10 body of water.

More specifically the invention relates to inflatable flotation devices of the type comprising a plurality of individual compartments inflated by air or other gas, for example, carbon dioxide 15 stored under pressure.

Inflatable flotation devices of the type in use prior to the present invention and of the construction embodying a plurality of inflatable compartments, have either been provided with 20 individual compartments supplied by separate sources of inflating medium or have been provided with intercommunicating compartments supplied from a single source of inflating medium.

The disadvantages of the first type of construction are at once apparent since the compartments, being individually inflatable, cannot be arranged for simultaneous release of the separate sources of inflating medium without more or less 25 complicated control apparatus; and since the duplication of the sources of inflating medium is both cumbersome and uneconomical.

With reference to the second type of construction having intercommunicating compartments supplied from a single source of inflating medium, 30 wherein the admission of inflating medium to one compartment will cause the medium to flow to all of the compartments, the undesirable feature is that, in the event of an accident causing puncturing and deflation of one compartment, the 35 remaining compartments will be immediately deflated, thus rendering the flotation device useless.

It is accordingly an object of this invention to provide an inflatable flotation device, such as a life-vest or belt, a life-boat or raft, or a flotation bag, or the like, having a plurality of inflatable compartments which are not in intercommunication but which are nevertheless adapted for simultaneous inflation.

It is a further object of the invention to provide a flotation device of the type mentioned in 40 which each of the separate compartments may be simultaneously inflated by pressure medium from a single pressure medium storage container.

It is a still further object of the present invention to provide a pressure medium distributing 45

manifold arranged to receive pressure medium from a source thereof and distribute it to a plurality of compartments and also arranged to prevent both reverse flow of the pressure medium from the compartments to the manifold and flow 5 between the compartments.

It is also an object of the invention to provide a structural embodiment thereof which is particularly adapted for use with life-boats or life-rafts.

It is still another object of the invention to provide another structural embodiment thereof which is particularly adapted for use with life-vests or life-belts.

These and other objects of the invention not 15 specifically enumerated above will be apparent as the invention is described in greater detail in conjunction with the accompanying drawings, wherein:

Figure 1 is a plan view of a life-boat or raft 20 embodying the present invention, and showing the manner of assembly of the pressure medium container and the distributing manifold.

Figure 2 is a longitudinal cross-sectional view of the life-boat taken on line 2—2 of Figure 1 25 and looking in the direction of the arrows, and showing upper and lower inflatable compartments.

Figure 3 is a considerably enlarged view, partially in section, showing the pressure medium 30 container connected to a distributing manifold in accordance with the invention.

Figure 4 is a partial sectional view of the distributing manifold of Figure 3 showing the manner in which the separate compartments of the 35 boat can be deflated.

Figure 5 is an outside end view of one of the manifold caps as shown in Figure 3.

Figure 6 is a view in elevation of a life-vest 40 embodying the present invention, and showing the manner of assembly of the pressure medium container and the distributing manifold.

Figure 7 is a somewhat enlarged view, partially in section, showing the pressure medium container and certain features of construction of a 45 distributing manifold in accordance with the invention.

Figure 8 is a still further enlarged cross-sectional view taken at right angles to Figure 7, and showing the pressure medium container and other 50 features of construction of the distributing manifold of Figure 7.

Referring first of all to Figures 1 and 2, the reference numeral 1 represents the inflatable rim 55 of an inflatable life-boat, the rim being provided

with individually but simultaneously inflatable upper and lower compartments 2 and 3, respectively, this arrangement of compartments enabling the boat to retain its original shape in the event that either one or the other of the compartments is punctured and deflated. The bottom of the boat is represented at 4, the oar-locks at 5, and the seats at 6, the seats being separately inflatable, in the construction shown, through suitable connections 7. At 8 is shown a pressure medium storage container suitably secured to the raft structure and provided with pressure medium release means 9. The release means is connected to a distributing manifold 10 which is connected by flanges 11 and 12 with the upper and lower inflatable compartments 2 and 3, respectively.

Referring now to Figure 3, it will be seen that the distributing manifold 10 has been swung around to a position at right angles to its position in Figure 1, so as to more clearly show its relationship to the pressure medium container in a single view. In Figure 3, the pressure medium release means is shown comprising a body member 8, a bonnet 13, and a bonnet coupling member 14. The body member 8 is provided with a passage 15, fitted at one end with a syphon tube 16 and normally closed at the other end by a frangible disc 17 and a sealing gasket 18 carried by a thimble 19 and held against a seat 20 at the end 30 of the passage 15 through the medium of a screw-threaded engagement of the thimble 19 with the body member 8. For the purpose of releasing the pressure medium from the container 8, disc rupturing means is provided in the form of a hollow tubular cutter 21 formed on a spindle 22 having a screw-threaded engagement with the bonnet 13. The hollow tubular cutter is shown provided with ports for permitting the passage of the pressure medium from the interior of the cutter to the outlet passage 23 when the cutter has been forced through the frangible disc 17. The bonnet 13 is provided with a packing nut 24, a packing washer 25, and packing 26 for preventing the leakage of pressure medium past the spindle. A metal to metal joint is sufficient for sealing the bonnet 13 to the body member 8. The outlet 31 is shown provided with a special recoil preventing tip 32 arranged to provide a balanced discharge of the pressure medium if the medium should be discharged when no conducting means is connected to the outlet, said recoil preventing tip forming no part of the present invention. The pressure medium release means assembly is completed by an operating handwheel 27 sealed 55 to a lug 28 on the body member 8 by a standard sealing wire 29 and lead seal 30. Of course, the syphon tube 16 is employed only with pressure mediums such as carbon dioxide stored in liquid form.

Still referring to Figure 3, the distributing manifold 10 is shown as an elongated member having a longitudinal passage 33 and a side outlet 34 located intermediate the ends of the manifold. As shown, the side outlet 34 is connected to the outlet 31 of the pressure medium release means by a nipple 35 and a coupling member 36. Each end of the passage 33 terminates in an enlarged chamber 37 of the manifold and is provided with a valve seat 38. As both ends of the manifold are of the same construction, only one end will be referred to as the description proceeds. Each chamber 37 is closed by a bonnet 39 by means of a screw-threaded engagement of the bonnet and the wall of the chamber. The bonnet 39 has a flange 40 adapted for a metal to metal seal with

the outer end surface of the manifold. The bonnet 39 is provided with a bore 41 and a valve seat 42, the purpose of which will presently be seen. The seat 38 at the end of the passage 33 is adapted to be engaged by a valve member comprising a tubular member 43 enlarged on its inner diameter at one end to hold securely a rigid disc 44 and a sealing gasket 45, preferably of soft rubber. The valve is kept normally seated by means of a coiled spring 46 bearing at one end on the disc 44 and at the other end on a valve member 47, which in turn engages the seat 42. The valve member 47 is preferably formed with a soft rubber seat, similar to the soft rubber sealing gasket 45. The valve member 47 is provided on one side with a projection 48 for guiding the spring 46, and on the other side with a hollow extension 49 provided with openings 50. The internal surface of the bonnet 39 is adapted for screw-threaded engagement with a plug bonnet 51, which latter carries a soft rubber gasket 52 adapted to effect a gas-tight joint with the outer end of the bonnet 39. Wings 53 are provided to facilitate making a hand-tight gas-tight joint. The left-hand end of the plug bonnet 51 is provided with a projection 54 terminating in three prongs 55, the purpose of which will be described in connection with Figure 4. Each end of the manifold 10 is provided with a side outlet passage 56 communicating with the chamber 37 between the valve seats 38 and 42. Encompassing each side outlet passage 56 is an enlarged flange 11 (or 12) for securing the manifold to the wall of the life-boat, one end of the manifold being secured as shown to the wall of the life-boat on each side of the dividing partition 57 between the upper and lower compartments 2 and 3, respectively. It is, of course, to be understood that the inflatable compartments of the life-boat are made of rubberized fabric and the connection to the wall of the boat is preferably made by securing the fabric between the flange 11 (or 12) and a companion flange 58 by means of screws 59 passing through the flange 11 (or 12) and the fabric and engaging the flange 58. Of course, each side outlet passage 56 communicates with one of the compartments 2 and 3 by means of a passage 60 passing clear through the flanges and the fabric wall of the life-boat.

With the construction as thus far described, when the handwheel 27 is turned to break the sealing wire 28, the cutter 21 ruptures the frangible disc 17 and permits the pressure medium to escape from the container 8 through the ports in the wall of the cutter through the outlet passage 23 and the nipple 35 to the passage 33 in the manifold 10. Here the flow divides, and the pressure of the medium raises the spring seated valve members at the ends of the passage 33 against the carefully balanced resistances of the coiled springs 46, whereupon the medium flows through the passages 56 and 60 to the respective inflatable compartments 2 and 3. The inflatable compartments 2 and 3 have, of course, a considerably larger volume than the pressure medium container 8. The pressure medium therefore expands and fills the compartments at a suitable pressure considerably lower than that originally contained in the container 8. However, as soon as the expansion has been completed and the pressure has been equalized throughout the system, the spring seated valve members at the ends of the passage 33 close under the influence of the coiled springs 46 and isolate the inflated compartments from the con-

tainer 8, from the manifold passage 33, and from each other. If, therefore, one of the compartments should be punctured and consequently deflated, this mishap will have no effect on the other compartment which is totally isolated therefrom; and, in view of the particular arrangement of the compartments so that both encompass the entire life-boat, deflation of one compartment will still allow the boat to retain its original shape, thus permitting it to continue its function as a life-boat.

With this construction, therefore, simple means are provided to inflate a plurality of compartments from a single source of inflating medium; in addition to which the dangers of intercommunicating compartments have been avoided.

When it becomes necessary to deflate the compartments, either totally, when the boat is to be stored away, or partially, when it is desired to relieve any excess pressure which has developed, the plug bonnets 51 are unscrewed and removed and the prongs 55 thereof are inserted within the bonnets 39 to engage the hollow extensions 49 on the valve members 47. By pressing on the thus reversed plug bonnets 51, the valve members 47 are unseated, thus permitting the pressure medium to flow from the inflatable compartments through the passages 60 and 56 and the openings 50 in the hollow extensions 49 of the valve members 47 out through the bonnets 39 to the atmosphere. Of course, each compartment may be deflated separately. Figure 4 illustrates the subject-matter just described, the right-hand end of Figure 4 showing the plug bonnet 51 just entering into engagement with the hollow extension 49 while the valve member 47 is still seated, and the left-hand end showing the other valve member 47 unseated.

If, on the other hand it is desired to further inflate the compartments, for example, to compensate for leakage of the inflating medium from the compartments, either plug bonnet 51 may be removed and a hand operated air pump, for example, may be connected in place of the plug bonnet, whereby air may be forced into a compartment through a valve member 47.

Figure 5 is, of course, a view of the plug bonnet 51 looking at it from the side on which the prongs 55 are provided.

The above, therefore, completes the description of the present invention as applied to a life-boat.

Referring now to Figure 6, which shows an inflatable life-vest embodying the present invention, the reference numeral 61 represents a complete inflatable life-vest ready for use. Of course, the invention may be adapted to any form of life-preserved, but the description is here concerned with a construction in the form of a life-vest. Still referring to Figure 6, the vest is constructed with two or more individually but simultaneously inflatable compartments 62, 63, the compartments being preferably symmetrically arranged to encircle the wearer's neck, so that there will always be an equal buoyant effect on either side of the wearer regardless of the number of compartments inflated or the degree of inflation.

At 64 is shown a pressure medium storage container suitably secured to the vest structure and connected by means of a coupling member 65 to a distributing manifold 66 which in turn is connected by fittings 67 and 68 and branch connec-

tions 69 and 70 with the inflatable compartments 62 and 63, respectively.

In Figure 8, the pressure medium release means is shown comprising the coupling member 65, which is secured within the mouth of the container 64, the coupling member being provided with a passage 71 communicating at one end with the interior of the container and normally closed at the other end by a frangible disc 72 and sealing gasket 73 carried by a thimble 74 and held against a seat at the end of the passage 71 through the medium of a screw-threaded engagement of the thimble 74 with the coupling member 65. For the purpose of releasing the pressure medium from the container, disc rupturing means is provided in the form of a cutter 75 provided with a bore 76 extending entirely therethrough. The cutter 75 is normally maintained out of contact with the frangible disc 72 by means of a coiled spring 77 bearing at one end in a recess 78 in the thimble 74 and at the other end on a head 79 of the cutter 75, outward movement of the cutter being limited by a washer 80 secured against an internal shoulder of the coupling member 65 by means of a ring-shaped member 81 having a screw-threaded engagement with the coupling member 65. A thin disc 82 of some easily fracturable material, such as bakelite, is secured between the washer 80 and the ring-shaped member 81, the purpose of the disc 82 being to protect the cutter 75 against the corrosive effect of external media and against the intrusion of foreign matter which might tend to clog the passage 76. In order to control the flow of the pressure medium from the container 64, the passage 76 in the cutter is made of a predetermined size, and the cutter 75 itself is arranged for a close-working fit on its external surface with the bore 83 in the thimble 74. The means for actuating the cutter 75 to cause it to rupture the frangible disc and permit the escape of the pressure medium will be described in connection with the assembly of the distributing manifold 66, in which this means is mounted.

As shown in Figures 7 and 8, the distributing manifold 66 comprises both means for distributing the pressure medium to the inflatable compartments of the vest and means for actuating the pressure medium release means. The latter means comprises a pointed striking pin 84 guided within a bore 85 of a member 86, which is threaded within the end of the manifold which is secured to the coupling member 65 by interengaging screw threads. The striking pin 84 is provided with a head 87 adapted to be engaged by a cam member 88 secured on one end of a shaft 89 which is journaled within cooperating bushings 90 and 91, of which the bushing 90 passes through a wall of the distributing manifold 66. Packing 92 held between the bushings 90 and 91 prevents leakage of the pressure medium past the shaft 89. Secured to the outer end of the shaft 89 is a lever 93 provided with an operating pull 94. The cam member 88 is normally maintained in its non-operated position by engagement with a groove 95 of the cam member of a catch button 96 guided within a recessed extension 97 of the manifold and maintained in contact with the cam member by means of a coiled spring 98. With the construction as thus described, when the pull 70 handle 94 is operated, the cam member 88 rotates against the yielding engagement of the catch button 96 and engages the head 87 of the striking pin 84, thus driving the striking pin through the fracturable disc 82 into engagement with the head 75

78 of the cutter 75, whereby the cutter is driven through the frangible disc 72, opening a passage for the pressure medium from the container 64 through the passages 71, 83 and 76, through openings 99 in the member 86 to the receiving chamber 100 of the distributing manifold, whence the medium discharges into the inflatable compartments 62 and 63 of the vest through the branch connections 69 and 70 and the fittings 67 and 68, 10 the flow of the pressure medium continuing until the pressure throughout the system has been equalized, at which time the compartments 62 and 63 are isolated from the receiving chamber 100 by the closing of check valves 101, located in 15 the branch connections 69 and 70, and corresponding to the check valves normally closing the ends of the passage 33 shown in Figure 3 of the previously described life-boat embodiment of the present invention. The construction of the 20 check valves 101 is not shown in detail, as, in the present instance, they are ordinary commercial pneumatic tire air valves; and it is sufficient to note that the check valves permit flow of the pressure medium to the inflatable compartments, 25 but prevent a reverse flow of the pressure medium from the inflatable compartments to the receiving chamber, at the same time preventing inter-communication of the inflatable compartments, which, in the event of the puncturing and deflation 30 of one of the compartments, would cause deflation of the remaining compartment.

Referring again to Figure 6, the reference numerals 102 and 103 represent tubes connected to the inflatable compartments 62 and 63 through 35 connections 104 and 105, through which tubes the inflation of the compartments of the vest may be maintained despite leakage of the inflating medium from the compartments. For this purpose the ends of the tubes 102 and 103 are arranged 40 near the neck-piece of the vest, so that they may easily be inserted in the mouth of a wearer for inflation by air from the wearer's lungs. Of course, if there is sufficient time to inflate the vest before the wearer must take to the water, 45 the vest compartments may be completely inflated through these tubes without operating the pressure medium container, so that the pressure medium may be reserved for a future more serious emergency, such as when the wearer is thrown 50 into the water without having time to inflate the vest, in which case a pull on the operating pull will effect rapid inflation of the vest.

The tubes 102 and 103 also serve to deflate the vest when it has served its purpose, the deflation 55 being effected by loosening the stoppers at the ends of the tubes.

At the time when the vest is deflated it is well to replace the empty pressure medium container 64 with a fully charged container. In order to 60 accomplish this, all that is necessary is to unscrew the empty container from the coupling 65 and replace it by a charged container, as the container and its release means comprise a replaceable unit. Care should be taken, however, that 65 the cam 88 has been returned to its normal position of engagement by the spring pressed catch button 96, so that it will not cause release of the pressure medium during the replacement process.

In completion of the description of the life-vest, it should be noted that the leak-proof fittings 67 and 68 each comprises a flanged thimble 106 threaded internally and externally, the threaded portion being passed through an opening in one of the fabric walls of the life-vest. A 70 soft rubber gasket 107, interposed between the

flange of the thimble 106 and the fabric wall, is compressed into gas-tight relationship with the flange and wall by means of a threaded ring 108 engaging the external threads of the thimble and bearing on a washer 109 which serves as a bearing plate for the threaded ring 108 permitting the latter to turn in a manner which would be impossible if the ring were in direct contact with the fabric wall of the vest. The assembly of the fitting also includes a sealing gasket 110 for insuring a gas-tight joint between the thimble 106 and the end-piece 111 of the branch connection 10 (or 69), which end-piece engages the internal threads of the thimble 106.

From the foregoing descriptions it will be seen that I have provided inflatable flotation devices which incorporate the objects set out at the beginning and which will be recognized to constitute a decided improvement over prior devices of this character. It will also be seen from the diversity of illustration that the principles of construction of the present invention are broadly applicable to various types of inflatable flotation devices; so that, while the invention has been described with reference to the accompanying drawings, I do not wish it to be limited save as defined in the appended claims.

I claim:

1. An inflatable flotation device comprising a unitary structure having a plurality of separate inflatable compartments to be inflated with a fluid medium, and distributing means for delivering the fluid medium thereto, the last named means comprising a chambered body member, means to secure the body member to the unitary structure, separate fluid conducting passages connecting each compartment with the body member, means in the body member associated with each said passage to prevent a reverse flow of the fluid medium from the separate compartments to the body member, a port in each said passage for connecting each said passage with the atmosphere at a point between its respective compartment and its reverse flow preventing means, means normally closing each said port, and means to open each said last named means for the purpose either of discharging fluid medium from the compartments to the atmosphere or of adding fluid medium thereto, said body member being adapted to receive fluid medium for initial substantially simultaneous distribution to the separate compartments.

2. An inflatable flotation device comprising a unitary structure having a plurality of separate inflatable compartments to be inflated with a fluid medium, and distributing means for delivering the fluid medium thereto, the last named means comprising a body member having an inlet passage adapted to receive a fluid medium for initial substantially simultaneous distribution to the separate compartments, means to secure the body member to the unitary structure, a plurality of distribution passages communicating with said inlet passage, each of said distribution passages terminating in an enlarged chamber of the body member and being formed with a valve seat within its respective chamber, means also formed with a valve seat extending within each said enlarged chamber and provided with a lengthwise passage, a fluid outlet passage connecting each inflatable compartment with one of the enlarged chambers at a point intermediate the aforesaid valve seats, a spring seated valve normally engaging each of the first named valve seats for preventing fluid flow from an inflatable compartment.

ment through the respective distribution passage back to the inlet passage but permitting flow from the inlet passage to the compartment, and a spring seated valve normally engaging each of the second named valve seats for normally preventing flow from an inflatable compartment to the respective lengthwise passage but adapted to be unseated through the lengthwise passage to permit flow from the compartment to the lengthwise passage when desired.

3. An inflatable flotation device comprising a unitary structure having two separate inflatable compartments to be inflated with a fluid medium, and distributing means for delivering the fluid medium thereto, the last named means comprising an elongated body member having a longitudinal passage extending therethrough and terminating in an enlarged chamber of the body member adjacent each end thereof, said longitudinal passage being formed at each end with a valve seat within the respective chambers, means also formed with a valve seat extending within each said enlarged chamber and provided with a lengthwise passage, a fluid outlet passage connecting each inflatable compartment with one of the enlarged chambers at a point intermediate the aforesaid valve seats, a spring seated valve normally engaging each of the first named valve seats for preventing fluid flow from an inflatable compartment to the longitudinal passage but permitting flow from the longitudinal passage to the compartment, a spring seated valve normally engaging each of the second named valve seats for normally preventing flow from an inflatable compartment to the respective lengthwise passage but adapted to be unseated through the lengthwise passage to permit flow from the compartment to the lengthwise passage when desired, and an inlet passage communicating with the longitudinal passage intermediate the first named valve seats for receiving a fluid medium for initial substantially simultaneous distribution to the separate compartments through the first named valve seats.

4. An inflatable flotation device comprising a unitary structure having a plurality of separate inflatable compartments to be inflated with a fluid medium, and distributing means for delivering the fluid medium thereto, the last named means comprising a body member having an inlet passage adapted to receive a fluid medium for initial substantially simultaneous distribution to the separate compartments, means to secure the body member to the unitary structure, a plurality of distribution passages communicating with said inlet passage, each of said distribution passages terminating in an enlarged chamber of the body member and being formed with a valve seat within its respective chamber, means also formed with a valve seat extending within each said enlarged chamber and provided with a lengthwise passage, a fluid outlet passage connecting each inflatable compartment with one of the enlarged chambers at a point intermediate the aforesaid valve seats, a spring seated valve normally engaging each of the first named valve seats for preventing fluid flow from an inflatable compartment through the respective distribution passage back to the inlet passage but permitting flow from the inlet passage to the compartment, a spring seated valve normally engaging each of the second named valve seats for normally preventing flow from an inflatable compartment to the respective lengthwise passage but adapted to be unseated through the lengthwise passage to permit

flow from the compartment to the lengthwise passage when desired, and bonnet members formed on one face with extensions adapted for screw-threaded engagement with the aforesaid lengthwise passages to close the same against communication with the atmosphere, and being formed on the other face with extensions adapted, by disengagement of the bonnet members and reversal thereof, to effect unseating of the second named spring seated valves to permit flow from the inflatable compartments to the atmosphere through the aforesaid lengthwise passages.

5. An inflatable flotation device comprising a unitary structure having a plurality of separate inflatable compartments to be inflated with a fluid medium, and distributing means for delivering the fluid medium thereto, the last named means comprising a body member having an inlet passage adapted to receive a fluid medium for initial substantially simultaneous distribution to the separate compartments, means to secure the body member to the unitary structure, a plurality of distribution passages communicating with said inlet passage, each of said distribution passages terminating in an enlarged chamber of the body member and being formed with a valve seat within its respective chamber, means also formed with a valve seat extending within each said enlarged chamber and provided with a lengthwise passage, a fluid outlet passage connecting each inflatable compartment with one of the enlarged chambers at a point intermediate the aforesaid valve seats, a spring seated valve normally engaging each of the first named valve seats for preventing fluid flow from an inflatable compartment through the respective distribution passage back to the inlet passage but permitting flow from the inlet passage to the compartment, and a valve seated by the same spring which seats a first named spring seated valve for normally preventing flow from an inflatable compartment to the respective lengthwise passage but adapted to be unseated through the lengthwise passage to permit flow from the compartment to the lengthwise passage when desired.

6. A collapsible life-boat comprising an inflatable tubular rim member, a bottom forming member, means dividing the tubular rim member into a plurality of inflatable compartments, a source of inflating medium, a discharge chamber mounted on the wall of the tubular rim member so as to lie within the boat when inflated, means to release the inflating medium from said source into said discharge chamber, fluid conducting passages connecting said compartments to said discharge chamber, automatically operable means associated with each fluid conducting passage to prevent flow of the inflating medium from the compartments to the discharge chamber, a port in each said passage connecting each said passage with the atmosphere at a point between its respective compartment and associated automatically operable means, means associated with each said port normally preventing flow of the inflating medium to the atmosphere, and means operable from within the boat to render the last named means inoperative.

7. A collapsible life-boat comprising an inflatable tubular rim member, a bottom forming member, means dividing the tubular rim member into a plurality of inflatable compartments, a source of inflating medium, a discharge chamber mounted on the wall of the tubular rim member so as to lie within the boat when inflated, means to release the inflating medium from said source

into said discharge chamber, fluid conducting passages connecting said compartments to said discharge chamber, automatically operable means associated with each fluid conducting passage to prevent flow of the inflating medium from the compartments to the discharge chamber, a port in each said passage connecting each said passage with the atmosphere at a point between its respective compartment and associated automatically operable means, and means associated with each said port normally preventing flow of the inflating medium to the atmosphere, said last named means being operable to open said ports.

8. An inflatable flotation device comprising a unitary structure having a plurality of separate inflatable compartments to be inflated with a fluid medium, and distributing means for delivering a fluid medium thereto, the last named means comprising a chambered body member, means to secure the body member to the unitary structure, separate fluid conducting passages connecting each compartment with the body member, means in the body member associated with each said passage to prevent flow of the fluid medium from the separate compartments to the body member, said body member being adapted to receive a fluid medium for distribution to the separate compartments, a port in each said passage connecting each said passage with the atmosphere at a point between its respective compartment and associated flow preventing means, means associated with each said port normally preventing communication of the compartments with the atmosphere, and means to render the last named means inoperative.

9. An inflatable flotation device comprising a unitary structure having a plurality of separate inflatable compartments to be inflated with a

fluid medium, and distributing means for delivering a fluid medium thereto, the last named means comprising a chambered body member, means to secure the body member to the unitary structure, separate fluid conducting passages connecting each compartment with the body member, means in the body member associated with each said passage to prevent flow of the fluid medium from the separate compartments to the body member, said body member being adapted to receive a fluid medium for distribution to the separate compartments, a port in each said passage connecting each said passage with the atmosphere at a point between its respective compartment and associated flow preventing means, and means associated with each said port normally preventing communication of the compartments with the atmosphere, said last named means being operable to open said port.

10. A fluid distributing manifold for a plurality of compartments comprising a chambered body member, a plurality of outlet passages leading therefrom, each adapted to be connected to a separate compartment, means in the body member associated with each said outlet passage to prevent flow of fluid from the separate compartments to the body member, said body member being adapted to receive a fluid medium for distribution to the separate compartments, a port in each said outlet passage connecting each said outlet passage with the atmosphere at a point between its point of connection to its respective compartment and its associated flow preventing means, and means associated with each said port normally preventing communication of the compartments with the atmosphere, said last named means being operable to open said ports.

DANIEL MAPES.
